UNITED STATES PATENT OFFICE.

ARTHUR ATWATER KENT, OF ARDMORE, PENNSYLVANIA.

LOUD SPEAKER.

Original application filed May 1, 1924, Serial No. 710,240. Divided and this application filed December 24, 1924. Serial No. 757,786.

To all whom it may concern:

Be it known that I, ARTHUR ATWATER KENT, a citizen of the United States, residing at Ardmore, county of Montgomery, 5 State of Pennsylvania, have invented certain new and useful Improvements in Loud Speakers, of which the following is a specification.

My invention relates to loud speakers, such 10 as telephones provided with amplifying horns utilizable in radio receiving apparatus and other relations.

This application is a division from my application Serial Number 710,240, filed May 15 1, 1924.

My invention resides in structure of the character hereinafter described and claimed.

For an illustration of one of the various forms my invention may take, reference is to 20 be had to the accompanying drawing, in which:

Fig. 1 is a side elevational view, partly in section, of a loud speaker embodying my invention.

25 Fig. 2 is a fragmentary vertical sectional view, on enlarged scale, of the base, telephone housing and lower portion of the horn section.

Fig. 3 is a fragmentary horizontal sectional view, partly in plan, taken on the line 30 3-3 of Fig. 2.

Referring to the drawing, H is the telephone housing, preferably of cast metal, as a die casting, closed at one end by the member 1, integral with which is the neck 2 having the sound passage 3 registering with the sound passage 4 in the horn section S, preferably of cast metal, and provided at its lower end with the integral sleeve 5 which 40 receives the neck 2, whereby the horn as a whole is supported directly and rotatable upon the telephone housing H.

At its end opposite to the end closure 1 the housing H is open, and interiorly threaded 45 to receive the exteriorly threaded cap C, or second housing member, preferably of molded insulating material, within which is carried the telephone magnet system comprising the permanent magnet M having the pole 50 pieces 6, 6, upon which are disposed the magnet coils 7, 7, whose terminals connect with the binding posts 8, 8, with which connect the terminals 9, 9 of the flexible telephone cord 10 extending through the central aperture 55 11 in the cap C. Disposed in the upper

end of the housing H is the telephone diaphragm T, controlled by the magnet system, and held between the resilient washers 12, 12 confined by the metal ring or washer 13 pressed upwardly by the undulating spring 14 engaging the upper or inner end of the cap C, which latter by rotation with respect to the housing H advances or recedes, thereby adjusting the poles 6 with respect to the diaphragm T and adjusting the pressure 65 exerted by the spring 14 upon the outer margin of the diaphragm T.

The telephone structure utilized may be of any suitable type or character, and the structure above described is merely an example 70 of one of various forms which may be utilized.

Upon the exterior of the housing H, preferably between its upper and lower ends, is the outwardly extending lug structure or flange 15, having the ears 16, into which are threaded the screws 17 extending through holes in the upper inwardly extending flange 18 of the hollow or bell-shaped base D, cheaply and simply formed of sheet metal 80 and preferably having at its lower end the bead or roll 19, at which it rests upon a table or other support. At 20 the base D is provided with an aperture through which the telephone cord 10 extends from the interior 85 of the cap C to the binding posts of the circuit which supplies the sound- or speech-representing current.

At the upper and large end of the horn section S it is provided with circumferentially spaced lugs or the circumferentially continuous flange 21, preferably inclined to the vertical, as indicated in Fig. 1. The bell or second section B of the horn structure is constructed of sheet material, preferably 90 metal, flaring from its small to its large end or mouth, where it is provided with the roll or bead 22. At its small end the bell B has the inwardly turned lugs or circumferentially continuous flange 23 abutting against 95 the lugs or flange 21 of the cast section S. Screws or equivalent means 24 secure the two sections S and B to each other at their abutting lugs or flanges. As indicated, the screws 24 are preferably threaded through 100 the lugs or flange 23 from the interior of the bell B into the lugs or flange 21 of the section S.

A horn comprising the sections S and B, of the character and structure described, is 110

simple, of low cost of manufacture, and yet fully effective for amplifying with small, if any, distortion the sound waves produced by the telephone diaphragm T.

5 By the combination of the character described there may be utilized for the base D sheet metal, as distinguished from more substantial cost metal bases, effecting substantial saving in cost, without sacrificing effectiveness. This is made possible by utilizing the telephone housing H as a connecting member between the base and the horn structure proper.

15 As indicated in the drawing, it is preferred that the base D be secured to the under side of the flange or lug structure upon the housing H, though it will be understood that the flange 18 of the base D may be disposed above the flange or lug structure 15.

20 What I claim is:

1. An amplifying telephone comprising a telephone housing, a diaphragm supported therein, a second housing member, a telephone magnet system secured thereon, a base 25 secured to said housing independently of said second housing member, and a horn separate from said base carried by said housing.

2. An amplifying telephone comprising a 30 telephone housing, a diaphragm therein, a cap adjustable upon said housing, a magnet system secured to said cap and adjustable therewith with respect to said housing and diaphragm, a base secured to said housing

35 independently of said cap, and a horn separate from said base carried by said housing.

3. An amplifying telephone comprising a 40 sheet metal base, a telephone housing to which said base is secured, a diaphragm in said housing, a second housing member independent of said base, a magnet system secured to said second housing member, and a horn separate from said base carried by said housing.

45 4. An amplifying telephone comprising a telephone housing, a diaphragm therein, a second housing member, a magnet system secured thereon, a base independent of said second housing member secured to said 50 housing intermediate its ends, and a horn

independent of said base carried by said housing.

5. An amplifying telephone comprising a sheet metal base having an inwardly extending flange, a telephone housing secured 55 to said flange, a second housing member independent of said base and flange, a magnet system secured on said second housing member, and a horn independent of said base carried by said housing.

6. An amplifying telephone comprising a telephone housing, an external flange on said housing, a sheet metal base having an inwardly turned flange secured to said housing flange, a second housing member independent of 65 said base, a magnet system secured to said second housing member, and a horn independent of said base carried by said housing.

7. An amplifying telephone comprising a 70 telephone housing, an external flange on said housing intermediate the ends thereof, a sheet metal base having an inwardly turned flange secured to said housing flange, a second housing member independent of 75 said base, a magnet system secured to said second housing member, and a horn independent of said base carried by said housing.

8. An amplifying telephone comprising a 80 telephone housing, lug structure on the exterior of said housing, a separate base secured to said lug structure, and a horn independent of said base carried by said housing.

9. An amplifying telephone comprising a 85 telephone housing, an external flange thereon intermediate its ends, a base having adjacent its upper end an inwardly turned flange secured to said housing flange, and a horn independent of said base carried by 90 said housing.

10. An amplifying telephone comprising a 95 telephone housing, a diaphragm therein, a magnet system therein, a cap carrying said magnet system and disposed on the lower end of said housing, a base secured to said housing above said cap, and a horn independent of said base carried by said housing.

ARTHUR ATWATER KENT.
